UNITED STATES PATENT OFFICE.

WILLIAM ERASTUS WILLIAMS, OF CHICAGO, ILLINOIS, ASSIGNOR TO WILLIAM D. JOHNSON, OF CHICAGO, ILLINOIS.

CONCEALED DOOR-CHECK.

1,147,909.

Specification of Letters Patent. Patented July 27, 1915.

Application filed April 2, 1914. Serial No. 829,623.

To all whom it may concern:

Be it known that I, WILLIAM ERASTUS WILLIAMS, a citizen of the United States, residing at Chicago, county of Cook, and 5 State of Illinois, have invented a new and useful Improvement in Concealed Door-Checks, of which the following is a specification.

My invention relates to that class of door 10 checks which are countersunk within the body of the door in a manner to conceal their appearance so that the door presents a smooth exterior and without any attachments which mar its appearance or collect 15 dust and dirt.

The object of my invention is to provide a check that will have the detailed merits hereinafter described and set forth in the claims, which merits enables the check to be 20 cheaply manufactured and become more efficient in service than any check heretofore made of its kind.

Reference will be had to the accompanying drawings in which—

25 Figure 1 is a top plan view of the top of the door mounted on its hinges partly open, at a time when the mechanism of the check is in a position locking the door against the action of the springs from closing it. Fig. 2 is an elevation of the top of the door broken away to expose a part of the check. Fig. 3 is an end view of the top of the corner of the door looking into the end of my check on section line 3—3 of Fig. 4. Fig. 4 is a 30 vertical elevation of the top of the door and door frame in section through the center of my check. Fig. 5 is a section line through 5—5 of Fig. 4. Fig. 6 is a section line through 6—6 of Fig. 4. Fig. 7 is a section 35 line through 7—7 of Fig. 4. Fig. 8 is a top plan view of the door when open to its widest limit, that of 180 degrees, and with the top corner of the door broken away to show a detail of construction. Fig. 9 is a 40 similar view to that of Fig. 2, with certain of the parts in a different position. Fig. 10 is a similar view to that of Fig. 1 when the door is closed, but with certain of the parts broken away to show details. Fig. 11 is a 45 plan section of a detail through the locking valve. Fig. 12 is a sectional detail on an enlarged scale through one of the pistons when same is in position of relieving the pressure within the checking cylinder. Fig. 13 is an enlarged size sectional view of 50

the gear of the locking valve. Fig. 14 is a vertical sectional detail showing the cross-head of the piston rods at its outmost limit of movement.

I prefer to make my check as narrow as 60 possible, and locate it in a small, narrow cavity running along the inside of the top of the door, but the check may be located at other positions in the door. It may be located in the bottom or the middle section of 65 the door, or wherever the construction will permit and location is desirable.

It is essential with a check of this class to reduce its thickness or size within such limits as will permit it being placed within 70 the body of doors of ordinary thickness, and to enable a thin check to be made is one 75 of the desirable things arrived at with my construction.

In the drawings, 1 indicates the body of the 75 door, 2 the door casing and 3 the threshold of the door; 4, 5 and 6 indicate the three tubes, which joined together, make the general body of my check. These tubes are connected at one end to the block 7 and at 80 the other end to the block 8, which when they are secured together act as one piece. Running along the top of the tube 4 there is a binding strip 9, which is carried down around the corner of the door by the leg 10, 85 and connected to one leaf 11 of the door hinge. The other leaf 12 of the hinge is connected to the door casing. A flat, tubular piece 13 connects the block 7 and strip 9 in a manner that the corner is filled out 90 uniting the tubes and strip 9 and leg 10, as it were in the one block, the strip 9 being fastened to block 7 at 14 and to the block 8 at 15. A strip 16 is fastened to the leaf 12 of the hinge, and extends up into an 95 angle running along the top of the door casing as indicated by 17, thus stiffening the inside of the door casing.

Into tubes 4 and 5 I place coiled springs 28 which furnish the energy to close the 100 door. The lower tube 6 acts only as a reservoir for holding the checking fluid. In the flat tube 13, there is mounted a cross-head 18, which is connected by the pin 19 to the link 20, which is connected to the pin 19 105 21 into a block 22, which is fastened into the strip 16.

Extending through the crosshead 18 there are the piston rods 23, which pass through stuffing boxes 24 in block 7, and pass through 110

the springs 28 and through the pistons 29, and terminate in heads 30, in a manner to form puppet valves in the pistons.

The springs 28 abut against the pistons 6 and block 7 and thus push the piston rods toward the outer ends of the tubes and thus, through the medium of the crosshead 18 and link 20, close the door, and in doing so apply a moment of leverage equaling the 10 distance from the center of the pin 21 to the center of the hinge 31. (See Fig. 1.) This moment of leverage slowly diminishes and is rather slight when the door is open to 180 degrees, as is shown by Fig. 8, but 15 correspondingly the pressure of the springs becomes greater as they are more and more compressed by the withdrawal of the crosshead 18, as the door is opened.

When the door closes under the influence 20 of the springs 28, the pistons compress the fluid which is in the chambers 32 in the ends of the tubes, and this fluid passes through the tube 4 to the tube 5 through the aperture 33, and the fluid of both tubes 25 passes through the hole 34 to the valve 35 and through the hole 36, and through the valve-aperture 38, controlled by valve 37, from whence it passes down through the holes 39 and 40 to the interior 41 of tube 6. 30 The valve 37 is an ordinary needle valve which moves by a screw thread permitting a greater or less passageway by it by simply turning the screw. The rapidity with which the fluid may escape and the door close is 35 controlled by this valve. The pistons are withdrawn when the door is opened and the fluid then passes from chamber 41 up through the aperture 42 and past the ball-valve 43 through the apertures 44 and 33, 40 thus filling the chambers 32, but on the return of the pistons the ball-valve 43 closes and thus the fluid is forced to travel in its escape under the influence of the springs from the chambers 32, through the passage- 45 ways before described past the valve 37.

It is desirable to be able to hold the door in any given position by means of the door check itself instead of locking devices which 50 are in contact with the floor, as is ordinarily used, so I provide a locking means in my check.

In the pathway of hole 36 I provide the valve or cock 35, which on its stem carries a pinion or small gear 45, which is actuated 55 by a rack 46, and under the influence of the rack the valve 35 may be turned to 90 degrees, thus closing the aperture and shutting off all escape of the fluid from the chamber 32 by route of the passageway 36.

60 The valve 35 is provided with a taper stem, which enables it to be easily made completely tight, and this stem is held down by a spring block 47, which is held in a dovetailed groove in the end of the strip 9. The 65 rack 46 is actuated through the means of

the rod 48, which passes along underneath the strip 9 and alongside the tube 4 in a manner not to widen the cavity in the door on account of this rod. The rod is connected to a lever 49 pivoted at 50 and provided with an angle projection 51 on its lower end that projects through a slot in tube 13 and into engagement with a push button block 52 which is accessible to be pushed by the finger when the door is partly open.

The rod 48 is provided with an extension 53 which projects outward from the door when the door is open and the push block 52 is pushed inward as the valve 35 is closed. The purpose of this is that when the door 70 is closed forcibly the end 52 will come in contact with the strip 16 and the act of forcibly closing the door will push the rod 48 and open the valve 35 by the contact of this end 53 with the strip 16. (See Figs. 1 80 and 2.)

Instead of unlocking the valve 35 by forcibly closing the door, as last described, it may be unlocked by pressing extension 53 of the rod 48.

When the door is forcibly closed faster than it will close under the influence of the springs forcing the fluid within the chambers 32 through the valve 37, there is danger of injury to the door hinges owing to the tremendous leverage due to the width of the door being so much greater than the distance from the center of the hinge pin 31 to the center of pin 21. Thus a safety escape or relief valve must be provided in this 95 class of door springs.

The safety relief valve is desirable with all door checks, but with many of the older type of check the weakest part is in the connecting links of the check, and their breakage is not so serious an accident as would be the case under careless treatment with checks of my class.

Where safety relief valves have heretofore been used they have generally been provided as separate and distinct mechanism, but in my case I make the piston rods and the piston heads and the main springs act as the relief valves, as will be understood from the construction shown. (See 105 Figs. 4 and 12.)

The piston head is made of the main piston piece 29, having a hollow stem 54 on which is placed the packing rings 55, together with an end ring 56, made of metal and in contact with the springs and taking the thrust from them, and thus compressing the packing rings 55.

The heads 30 of the piston rods 23 are fitted to seat at 57 in the piston heads and make a tight closure with the aperture 58 through the stem 54. The apertures 58 of the pistons are larger than the piston rods, and thus when the rods are in position shown by Fig. 12 there is an escapement 115 120 125 130

from the chamber's 32 through the apertures 58 of the piston head.

When the door is forcibly closed at a time when the valve 35 is closed, or when the door 5 is closed faster than the escape will permit past the valve 37, when the valve 35 is open, then the pressure on the piston heads becomes very great, and the heads 30 of these rods generate so much pressure in the chamber 32 that this pressure working against the piston heads 29, outside of the heads 30 of the rods, will force back the springs 28, allowing the piston rods to project as shown in Fig. 12, thus permitting the escape of the 15 fluid through the aperture 58 past the pistons and allowing the door to be closed without injury to the hinges.

Any fluid that passes the pistons within the tubes 4 and 5 will run down by gravity 20 through the holes 59 that connect the three tubes together, and thus this fluid will drop down through to the reservoir tube 6 from whence it is drawn as needed, up or past the ball-valve 43.

25 To prevent escape of the fluid around the piston rods through the block 7, the rods are packed by the packing 60, compressed by the glands 61.

When the door is open, say beyond 120 30 degrees and the valve 35 is then locked or closed, locking the door in a fixed position open, the position of the crosshead 18 and link 20 would then be such as were the door forcibly closed, the lines of pressure developed 35 would not exert sufficient pressure on the piston rods to operate the safety relief before described without danger to the fastening of the hinges, hence I provide an un-locking device for the valve 35 that will au-

tomatically unlock or open said valve whenever the door is opened beyond a safe limit, after said valve 35 has been closed. This 40 unlocking mechanism consists in the tube 62, spring 63, stud 64 and pin 65. When the

45 crosshead 18 approaches the outward limit of its travel the pin 65 on the lower side of the crosshead abuts against the shoulder 66 of the tube 62, and on further movement carries with it the tube 62, compressing the

50 spring 63 against the block 52, and thus moving the lever 49, thereby actuating the rod 48 and its rack 46, turning the pinion 45 and opening the valve 35, (see Figs. 4 and 14) the latter figure showing a position

55 of the parts when the door is open as indicated by Fig. 8, the view 14 being taken in a direction of the arrow 69, Fig. 8. Any further movement of the crosshead 18 and its pin 65 after the limit of movement of

60 the block 52 is arrived at, is taken up by the spring 63 compressing to accomplish such movement. The stud 64 serves only as a guide for the end of the tube 62.

65 The tubes 4, 5 and 6 are nicely fitted into the blocks 7 and 8 and are secured therein

by means of the rivets 67 and 68 that pass through the blocks and margins of the tubes in a manner locking the parts together against the end thrust of the springs. These rivets 67 and 68 are shown on dotted lines 70 in Fig. 6. The tubes are fitted tightly into the said blocks to prevent leakage of the fluid around these joints.

The block 7 is fastened to the strip 9 at 14, and the block 8 to strip 9 by a screw 15. 75 (See Figs. 1 and 4).

The two tubes 4 and 5 and springs and pistons work together as one, and thus I am enabled to get a powerful thrust for closing the door within a narrow space or counter-sink in the door which is a great desideratum.

The fluid of door checks of this class, or any class for that matter, escapes by evaporation and leakage, and it is very desirable to have a check so constructed that all chance for the escape of the fluid be prevented as much as possible, so I have designed my check in a form that there are no joints below the normal level of the fluid 90 in the check when in use that might permit the escape of the fluid by gravity, thus eliminating any chance of a fault in a packed joint permitting accidental escape of the fluid as is a danger when such packed joints 95 are located below the level of the fluid of the check when in use. For illustration, some checks have a piston rod or other articulating member passing through a stuffing box, below the normal level of the fluid and rely 100 on the packing to keep the joints tight and prevent the escape of the fluid when the check is in service. Such construction I avoid.

An adjustment of the tension of the 105 springs of my check may be arrived at for considerable variation in tension by screwing the piston rods 23 through the threads 70 in the crosshead 18. This is done by means of a wrench adapted to fit on the 110 squared ends 71 of the piston rods.

What I claim is:

1. A door check countersunk within the door and provided with a series of tubes for forming the checking chamber and a reservoir chamber for holding the checking fluid, said tubes connected at their ends to blocks which hold the tubes together as one member; with passageways for the passage of the fluid between the chambers of the tubes 115 and an adjustable valve for controlling the escape of the fluid between the tube which acts as the reservoir tube and the checking chambers of the cylinder tubes.

2. A door check countersunk within the 125 door and composed of a plurality of tubes disposed in a manner to be confined within a narrow space in a door, a plurality of pistons and springs within the tubes; with an adjustable escape valve located at the top of 130

the tubes whereby access may be had at the top of the door to adjust the escape valve.

3. A door check countersunk within the door composed of a plurality of checking cylinders lying one above the other within the door and connected together to act as one, an adjustable escape valve controlling the escape of the fluid from the cylinders, and an independent locking valve for closing entirely the escape of the fluid from the cylinders.

4. A door check countersunk within the door and composed of a plurality of tubes forming the body of the check a plurality of springs and pistons within the tubes and a single entrance and a single escape passage for the sections of the tubes which act as checking chambers; with a checking valve controlling the entrance passage and a locking valve and an adjustable escape valve for controlling the escape passageway.

5. A door check countersunk within the door comprising a plurality of springs and checking cylinders and a plurality of rods for connecting the springs to a single cross head, said rods being adjustable in relation to the said cross head so that the tension of the springs may be adjusted, said adjusting means being located in the edge of the door, accessible for adjusting purposes when the door is open.

6. In a door check of the class described a plurality of tubes arranged one above the other in a manner to form a thin body that may be placed within the body of the door the upper tubes forming cylinders for checking purposes and the lower tube forming a reservoir chamber; with a plurality of springs, pistons and piston rods located in the upper tubes and passageways on each side of the pistons between the upper tubes and the reservoir tubes the passageways on one side controlled by the two systems of valves whereby the fluid from the reservoir chamber may be drawn to the upper tubes through a checking valve from the reservoir tube and be forced back into the reservoir tube through a passageway controlled by an adjustable escape valve, whereby the rate of the escape and the corresponding time consumed in closing the door by the action of the springs may be lengthened or shortened by the adjustment of the escape valve.

7. In a door check of the class described a chamber for holding a spring, mounted along the top of the door, a piston within the chamber controlled by the action of the spring, a passageway or a bypass connecting the section of the chamber in front of the piston around to that section of the chamber in the rear of the piston said bypass controlled by an automatically operated check valve and an adjustable escape valve, the said escape valve adjustable in a line at right angles with the line of the piston

travel in a manner that access may be had from the edge of the door to adjust the escape valve.

8. In a fluid door check a safety relief valve for releasing the pressure when the door is forcibly closed beyond the rate permissible by the escape valve, which safety relief valve is located within the piston head and held shut by the main actuating spring of the check.

9. In a liquid door check wherein the door is closed by the action of a spring and the rate of travel of the spring in closing the door is controlled by a piston working in a cylinder, a safety relief valve for the chamber of the cylinder which valve is formed by means of the piston rod head's closure with the piston head and the latter held in contact with the rod by the energy of the main actuating spring of the check.

10. In a door check wherein the door is closed by the action of a spring and the closing action of the spring is limited by the movement of a piston working within a chamber discharging a fluid body out of the chamber as the door is closed; a safety relief valve located within the piston head and held closed by the pressure of the main actuating spring in contact with the piston head; and an adjustable escape valve controlling the rate of discharge of the fluid from the chamber as the spring forces the piston to evacuate the chamber.

11. In a door check wherein the closure of a door is effected by a spring and the rate of travel of the spring controlled by a piston working in a cylinder and discharging a fluid from the cylinder, a safety relief valve located within the piston and held normally shut by the action of the main actuating spring of the check; with an adjustable escape valve and a locking valve controlling the fluid in its escape from the cylinder.

12. In a check of the class described a locking valve for locking the escape passage of the fluid from the checking chamber which locking device is composed of a valve revolving in the escape passageway from a checking chamber and a rack and pinion movement for controlling the action of this valve.

13. A door check wherein a spring closes the door and the rate of closure is controlled by the escape of a fluid from a chamber evacuated by a piston actuated by the spring; a locking device for shutting off entirely the escape of the fluid from the chamber thus arresting the further closure of the door by the spring; an unlocking device for unlocking the locking device, said unlocking device being operated by a movement of the door in the opening direction after the door has been opened beyond a safe limit for the locking device to remain in force.

14. In a concealed door check the combination of an actuating spring, a checking chamber located within the body of the door, a link connecting the door casing with a cross head mounted to reciprocate within the body of the door, suitable intermediate connecting mechanism for connecting the cross head to the springs whereby on the opening of the door the cross head is withdrawn and the springs are compressed and on closure of the door the springs draw in the cross head; a locking device for locking the door in a given position against the movement of the door under the influence of the springs and an unlocking device for unlocking the locking device the same automatically unlocking the locking device through the means of the cross head when the latter moves in the region of its outermost limit.
15. In a door check of the class described located within the body of the door, a checking chamber composed of a cylinder within
- which there is fitted a piston and spring for actuating the piston in the chamber and a reservoir chamber located below the checking chamber and connected by passageways on each side of the piston travel and a check valve for controlling the entrance of the fluid to the checking chamber and a separate escape passageway or by-pass around the checking valve; with two valves located in this escape or by-pass passageway, one of them for shutting entirely the passageway and the other being adjustable for controlling the size of the orifice in the escape passageway.

In witness whereof, I have hereunto signed my name this 13th day of March, A. D., 1914, in the presence of two subscribing witnesses.

WILLIAM ERASTUS WILLIAMS.
